ELECTRICAL CONDUCTOR CONNECTOR

Dallas P. Shappell, Milwaukee, Wis., assignor to
McGraw Electric Company, a corporation of
Delaware

Application October 4, 1945, Serial No. 620,313

4 Claims. (Cl. 24—125)

1

This invention relates to electrical connectors of the type in which a slotted or bifurcated bolt receives the conductors to be connected and in which a plunger or head slides in the slot of the bolt and is forced into binding engagement with one of the conductors to thus tightly clamp the conductors together and to adjacent parts of the connector.

Objects of this invention are to provide a slotted bolt connector in which the sliding plunger or head prevents collapse of the legs of the slotted bolt and also acts in conjunction with such legs to lock the nut against inadvertent loosening even when the conductors are subjected to considerable swaying or jarring.

Further objects are to provide a connector in which the head or sliding plunger is stamped from flat stock and is easily shaped or bent to the desired form and is so made that cam portions are provided which are automatically drawn into the slot of the bifurcated bolt and slightly spread the arms thereof, when the nut is tightened, to thus lock the nut against loosening.

An embodiment of the invention is shown in the accompanying drawings, in which:

Figure 1 is a sectional view through the connector shown in position clamping two conductors together and against adjacent parts of the connector, the sliding head being shown in full except for a small portion thereof.

Figure 2 is a sectional view on the line 2—2 of Figure 1 with the nut shown in section.

Figure 3 is a bottom view of the structure shown in Figure 1.

Figure 4 is a sectional view on the line 4—4 of Figure 1.

Referring to the drawings it will be seen that the connector comprises a threaded and slotted bolt 1 having a pair of spaced arms 2. A nut 3 is screwed on the bolt and is arranged to force a head or sliding plunger, indicated generally by the reference character 4, into binding engagement with one of the conductors 5 to thus clamp such conductor against the conductor 6 and clamp both conductors against the adjacent portions of the connector.

The sliding plunger 4 is a stamping and is stamped from flat stock. It is provided with a transverse portion 7 which may be slightly dished or channelled as shown in Figures 1 and 2, which is arranged to engage the conductor 5, and with outwardly extending looped portions 8 which, as may be seen from Figure 4, are wider than the slot in the bolt and prevent lateral displacement of the sliding head or plunger. From the looped

2

portions 8, arms 9 extend inwardly and lengthwise of the slot in the bolt and terminate in outwardly projecting cam portions 10, each of which has slanting cam surfaces on opposite sides thereof as indicated at 11. These cam portions 10 are slightly less in width at their inner ends than the slot in the bolt and gradually widen as their outer ends are approached so that their outer portions are slightly wider than the slot in the bolt. These cam portions 10 are also angularly bent outwardly and slightly overlap the nut 3 so that the nut is loosely held between the portions 8 and 10.

The sliding head or plunger 4 is made of resilient metal so as to allow a certain relative motion of its parts when the nut 3 is tightened as will appear hereinafter.

When the nut 3 is tightened it bears with considerable pressure against the outer parts of the looped portions 8 and slightly closes the inwardly directed ends thereof. This causes the arms 9 to rock inwardly and draws the gradually tapered cam portions 10 inwardly, thus slightly spreading the arms 2 of the bolt apart. This not only neutralizes any tendency for the arms 2 to move towards each other due to the reaction of the threads of the bolt and the threads of the nut, but, as stated, actually spreads the arms apart a slight amount. This outward spreading of the arms 2 of the bolt causes the arms to lock the nut 3 against inadvertent unscrewing.

By properly proportioning the parts and by selecting the desired angle of slant for the cam faces 11 of the cam portions 10 any desired degree of pressure can be exerted on the arms 2 of the bolt to thus secure the exact degree of interlocking desired between the spread arms of the bolt and the nut.

A further advantage is taken of the resilient nature of the plunger or sliding head 4. The looped portions 8 thereof provide a considerable amount of spring or yield. Thus it is apparent that when the nut is tightened, the portions 8 yield and hold the conductors 5 and 6 in contact with each other in a yielding manner. This is particularly advantageous because it has been found that where there is relative motion between the conductors due to vibration, swinging or other movement to which the conductors are frequently subjected, there is a considerable amount of wear after a length of time. It has been found that with non-yielding connectors it frequently happens that the conductors, after being subjected to extended wear, are not held in the proper intimate contact with each other.

This defect is wholly overcome by this invention as the plunger 4 due to its yielding nature maintains the conductors in intimate, firm contact with each other at all times although wear may have occurred.

It will be seen that a novel form of electrical connector has been provided by this invention, which is of very simple construction, which can be easily produced, and which can be most easily applied to the conductors.

It is to be particularly noted that this invention provides a novel form of sliding head or plunger for the connector, which in addition to acting in its usual capacity to clamp the conductors also coacts with the nut and arms of the bolt to securely lock the nut on the bolt against inadvertent loosening.

Although this invention has been described in considerable detail, it is to be understood that such description is intended as illustrative rather than limiting, as the invention may be variously embodied and is to be interpreted as claimed.

I claim:

1. An electrical connector comprising a slotted bolt having a pair of spaced arms adapted to receive conductors therebetween, a sliding head adapted to slide in the slot of said bolt, said head having movable cam means arranged to laterally enter the slot of said bolt, and a nut screwed on said bolt and arranged to force said head inwardly to cause binding of said conductors, said nut being arranged to force said cam means laterally between the arms of said bolt to force said arms apart and cause binding interlocking between said arms and said nut.

2. A connector for connecting electrical conductors comprising a slotted and threaded bolt having a pair of spaced arms adapted to receive conductors therebetween, a sliding head slidable between said arms, and a threaded nut coacting with said bolt to force said head into binding relation to said conductors, said head having a transverse portion extending between said arms and having outwardly located looped portions continuing as a pair of arms provided with cam portions arranged to laterally enter the slot of said bolt, said nut when screwed tightly against said head causing said looped portions to slightly yield and causing said cam portions to

move inwardly of said slot to spread the arms of said bolt and cause binding interlocking between the arms of said bolt and said nut.

3. A connector for connecting electrical conductors comprising a slotted and threaded bolt having a pair of spaced arms adapted to receive conductors therebetween, a sliding head having a transverse portion located in the slot of said bolt and having inwardly looped portions on opposite sides of said bolt and having arms extending longitudinally of said bolt and located within the slot of said bolt, the arms of said head having gradually tapered cam portions at their ends arranged to be moved laterally inwardly of the slot of said bolt, and a threaded nut coacting with said bolt and bearing upon said sliding head adjacent said looped portions to force said head into binding relation to said conductors and to cause the arms of said head to rock inwardly to draw said cam portions into the slot of said bolt to spread the arms of said bolt to thereby lock said nut against unscrewing.

4. A connector for connecting electrical conductors comprising a slotted and threaded bolt having a pair of spaced arms adapted to receive conductors therebetween, a sliding head having a transverse portion located in the slot of said bolt and having a pair of arms arranged to be moved with respect to said transverse portion, the arms of said head having cam portions arranged to move laterally into the slot of said bolt, and a threaded nut coacting with said bolt for forcing said transverse portion into binding relation to said conductors and for moving the arms of said head to force said cam portions laterally in between the arms of said bolt to spread the arms of said bolt to thereby lock said nut against unscrewing.
